his Attorney.

UNITED STATES PATENT OFFICE

2,178,912

WIRE CLEANING DEVICE

Francis P. Leahey, Worcester, Mass., assignor to
 The American Steel and Wire Company of New
 Jersey, a corporation of New Jersey

Application April 23, 1938, Serial No. 203,943

6 Claims. (Cl. 51—150)

This invention relates to a cleaning or wiping device, and particularly to a device for cleaning continuous length stock, such as wire and the like.

5 In the process of wet wire-drawing, an oxide film, coating or thin scale is formed on the surface of the wire which is very undesirable in that it interferes with succeeding finishing operations thereon. This is particularly objectionable to wire that is to receive a coating of enamel. Heretofore, this film or coating has usually been removed by annealing; but this involves excess handling and increases the production time which is, of course, very expensive 10 as well as inconvenient.

According to the present invention, this film or coating can be removed from the surface of the wire by placing the improved wiping or cleaning device of my invention in a suitable location 20 in the production line, preferably immediately after the wire-drawing machine and allowing the wire to pass therethrough.

It is an object of this invention to provide an improved wiping device which quickly and inexpensively cleans the surface of continuous length wire.

It is another object of the invention to provide an adjustable wiping device for cleaning wire and the like which will adjust itself relative to 30 the wire as it passes continuously therethrough.

Various other objects and advantages of this invention will more fully appear during the course of the following specification and will be particularly pointed out in the appended claims.

35 In the accompanying drawing, I have shown, for the purpose of illustration, one embodiment which my invention may assume in practice.

In the drawing:

40 Figure 1 is a plan of the improved cleaning device of my invention;

Figure 2 is a section taken on line II—II of Figure 1;

Figure 3 is a section taken on line III—III of Figure 2, and,

45 Figure 4 is a section taken on line IV—IV of Figure 2.

The improved wiping and cleaning device of my invention, as shown in the drawing, comprises an elongated rectangular shaped box or 50 container 2 made from any suitable material, preferably of metal, which is adapted to hold a quantity of loose abrasive material 3, preferably very fine sand or the like. At one end of the container and on the inside thereof, there is 55 arranged a sleeve-like annular member 4 hav-

ing a flanged portion 5 on one end thereof by which it is attached to the inner end wall of the container 2, a smaller flanged portion or collar 6 on the outer end thereof, and an axial opening 7 through the center thereof through which the continuous length wire 8 is adapted to pass. There is arranged on the annular member 4 a movable sliding collar 9 having a plurality of hooks 10 extending inwardly toward the center of the container. There is also positioned on 10 this annular collar 4, between the sliding collar 9 and the small outer flanged end 6 of collar 4 a coil spring 11.

On the inner wall of the opposite end of the container, there is arranged a similar sleeve-like annular member 12 having a flanged end 13 by which it is attached to the inner end wall of the container 2. There is arranged within this annular member a rotatable sleeve-like twisting member 14 having a flanged portion 15 20 on the outer end thereof which is adapted to abut against the outer end of the annular member 12 and an axial opening 22 through which the wire is adapted to pass. This outer flanged portion 15 carries a plurality of hooks 16 extending inwardly toward the center of the container, similar to the hooks 10. The twisting head 14 is of such length that it extends through the outer wall of the container and has positioned thereon, outside the end of the container, preferably a washer 17 and a handle or twisting wheel 18 held thereon preferably by means of a lock nut 19. There is arranged between each of the oppositely disposed hooked portions 10 at one end of the container 16 on the opposite end 30 of the container, cord-like fabric wipers 20, preferably made of cotton or some other cellulose material.

The improved wiping and cleaning device of my invention operates as follows:

40 A wire 8 is fed, preferably from the wire-drawing machine, into the container, through the opening 22 in the annular twisting member 14, through the abrasive material or sand therein, through the opening 7 in the opposite end of the container, and out of the container to a wire-drawing block or to the next operation. After the wire is properly threaded and positioned in the container, the cord-like lengths of cotton or fabric material are suitably twisted around the 45 outer surface thereof by turning the handle 18. The lengths of wiping material are wrapped around the wire in such a manner that they allow the loose particles of sand or abrasive material to fall between the wrappings, thereby allowing the 50 55

wire to pick up these loose particles as it passes therethrough, cooperating with the wrappings of the lengths of material to clean the film or scale from the wire. After the lengths of wiping material have been properly twisted and wrapped about the wire, the twisting head 14 is locked in position by means of a locking machine screw 23 carried by the annular member 12. It will be seen that as the twisting head 14 is rotated to twist the lengths of wiping material about the wire, the sliding collar 9 will move to the left against the action of the coil spring 11 carried by the annular member 4, thereby keeping the lengths of wiping material taut and securely wrapped about the wire. The wire is then drawn continuously through the device to clean the surface of the wire.

As a result of my invention, it will be seen that this improved wiping device can be located at any desirable point in the production line and the wire conveniently and efficiently cleaned without removing the wire therefrom for the purposes of cleaning by annealing or any other conventional means.

While I have shown and described an embodiment of my invention, it will be understood that this embodiment is merely for the purpose of illustration and description and that various other forms may be devised within the scope of my invention as defined in the appended claims.

I claim:

1. A cleaning device of the class described comprising a container for holding a quantity of loose abrasive material, a plurality of lengths of fibrous material and a means for holding and twisting the lengths of said fibrous material around the article to be cleaned so as to completely encircle and contact the outer surface thereof, said fibrous material adapted to cooperate with said abrasive to clean the surface of the article as it passes therethrough.

2. A cleaning device of the class described comprising a container for holding a quantity of loose abrasive material, a fibrous material, means for holding and twisting said fibrous material around the article to be cleaned so as to completely encircle and contact the outer surface thereof, said fibrous material adapted to cooperate with said abrasive to clean the surface of the article as it passes therethrough.

3. A cleaning device of the class described comprising a container for holding a quantity of loose abrasive material, a plurality of lengths of fibrous material, means for holding the ends of each of said lengths of fibrous material in said container, at least one of said holding means being yieldable, and means for twisting said fibrous material around the article to be cleaned so that said fibrous material completely encircles and contacts the outer surface thereof, said fibrous material adapted to cooperate with said

abrasive to clean the surface of the article as it passes therethrough.

4. A cleaning device of the class described comprising a plurality of lengths of fibrous material, means for holding and twisting said material around the article to be cleaned so as to completely encircle and contact the outer surface thereof, said fibrous material adapted to clean the surface of said article as it passes therethrough.

5. Apparatus for cleaning a continuous length article including, in combination, an elongated container for holding a quantity of loose abrasive material, an elongated member of pliable material arranged in said container, yieldable means arranged on the delivery end of said container to which one end of said pliable material is attached, and a rotatable means arranged on the opposite receiving end of said container to which the opposite end of said pliable material is attached, said pliable material adapted to be twisted around the continuous length article against the action of said yieldable means upon rotation of said rotatable means so that said pliable material will completely encircle and bear against the outer surface thereof, whereby said pliable material will cooperate with the abrasive material in said container to clean the surface of the article as it is continuously drawn therethrough.
